UNITED STATES PATENT OFFICE.

ORRIN B. READ, OF CHARLOTTE, VERMONT.

DESIGN FOR A LINE-SUPPORTER.

SPECIFICATION forming part of **Design No. 24,880**, dated **November 12, 1895**.

Application filed September 6, 1895. Serial No. 561,706. Term of patent 14 years.

To all whom it may concern:

Be it known that I, ORRIN B. READ, a citizen of the United States, residing at Charlotte, in the county of Chittenden and State 5 of Vermont, have invented a certain new and original Design for Line-Supporters; and I do declare the following to be a full, clear, and exact description of the invention.

My invention relates to a new design for a line-supporter.

Figure 1 is a side elevation of my line-supporter, and Fig. 2 is a sectional view taken on line *x-x* of Fig. 1.

The design consists of a line-supporter of 15 the configuration and shape shown in the accompanying drawing, in which I have represented my design in perspective.

The leading feature of my design is a bar 1, slightly curved in the direction of its length, having a flat side 2 and an oval side 3, and 20 provided at its lower end with an outwardly-projecting stud 4, having a rounded head 5.

What I claim is—

The design for a line supporter, as herein shown and described.

In testimony whereof I affix my signature in presence of two witnesses.

ORRIN B. READ.
